ADVERTISING DISPLAY STAND FOR DISPLAYING FLASHLIGHTS OR THE LIKE

Jack E. Pollard, Norwalk, Conn.

Application June 25, 1958, Serial No. 51,524

Term of patent 14 years

(Cl. D80—9)

The figure is a perspective view of an advertising display stand for displaying flashlights or the like showing my new design.

I claim:

The ornamental design for an advertising display stand for displaying flashlights or the like, substantially as shown.
